UNITED STATES PATENT OFFICE.

JOHN S. MULLIN, OF PORT MONMOUTH, NEW JERSEY.

IMPROVEMENT IN STEAM-GENERATORS.

Specification forming part of Letters Patent No. 74,404, dated February 11, 1868.

To all whom it may concern:

Be it known that I, JOHN S. MULLIN, of Port Monmouth, in the county of Monmouth and State of New Jersey, have invented a new and Improved Steam-Boiler; and I do hereby declare that the following is a full, clear, and exact description thereof, which will enable those skilled in the art to make and use the same, reference being had to the accompanying drawings, forming part of this specification.

This invention relates to a new and improved construction of steam-generators for either locomotive or stationary purposes, but which has more particular reference to boilers for locomotive-engines; and it consists in the arrangement of the fire-flues and construction of the fire-box and the smoke or combustion chamber, and in the devices for arresting the sparks and returning them to the fire-box, whereby many advantages are secured, as will be hereinafter more fully described.

Figure 1 is a vertical longitudinal section of the boiler through the line *x x* of Fig. 2. Fig. 2 is a vertical section of Fig. 1, through the line *y y*. Fig. 3 is a vertical section of Fig. 2, through the line *z z*.

Similar letters of reference indicate corresponding parts.

A is the shell of the boiler. *B* represents the fire flues or tubes of the boiler. *C* is the fire-box. *D* is the smoke or combustion chamber.

By inclining the tube-sheet of the fire-box and the smoke-chamber, as seen in the drawings, I am enabled to set the tubes in an inclined position, which, for the proper combustion of the fuel and the generation of steam, is conceded to be far better than the horizontal position.

By this arrangement the tubes may be inclined and stand at right angles with the tube-sheets, which allows of the proper setting of the tubes, and secures a good and perfect joint.

The tube-sheets are marked *a a*.

E is the smoke-stack or chimney, which

drops down to the bottom of the smoke-chamber, with a suitable opening at the lower end for the admission of the smoke.

F is a double deflector attached to the smoke-stack, (within the chamber,) which divides the current of smoke and sparks which are discharged from the flues *B*. One side of this deflector *F* is seen in Fig. 1, where the course of the sparks is indicated by the arrows, being guided, by the flange and scroll *G*, into the channel *H*, through which they are projected, by the difference of pressure due to a partial vacuum produced in the fire-box by the current of air produced by exhausting the steam, into the smoke-stack.

But other provision is made for forcing the sparks from the smoke-chamber and returning them to the fire-box.

At the base of the stack *E* and smoke-chamber the channel *H* is connected with an air-flue *J*, which extends, in front of the boiler or smoke-stack, to a funnel shape, as seen at *K*. When the locomotive is in motion, the air entering the funnel will be compressed and forced, by the speed, into the channel *H*, thus forcing a current from the chamber *D*, and carrying the sparks back to the fire-box.

Having thus described my invention, I claim as new and desire to secure by Letters Patent—

1. The inclined fire-tubes *B* and inclined tube-sheets *a a*, in combination with a steam-boiler, substantially as shown and described.

2. The extension of the smoke-stack or chimney of a steam-boiler near the bottom of the smoke-chamber, substantially as shown and described.

3. The double deflector *F*, whereby the sparks are conducted into the channel *H*, substantially as described.

The above specification of my invention signed by me this 20th day of November, 1867.

JOHN S. MULLIN.
